DESIGN FOR A DRESS

David Crystal, New York, N. Y.

Application August 17, 1938, Serial No. 79,385

Term of patent 3½ years

To all whom it may concern:

Be it known that I, David Crystal, a citizen of the United States of America, residing in the city of New York, county of New York, and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

My design comprises an all over tucked dress of the instant configuration having grouped tucks on the shoulders and on the rear neckline and four tucked flaps on the bust portion in combination with the specific belt member as shown.

I claim:

The ornamental design for a dress, substantially as shown and described.

DAVID CRYSTAL.
